Patented Dec. 2, 1969

216,231

HOUSING FOR FIRE DETECTOR

Stephen G. Hauser, Van Nuys, Calif., assignor to Direct Markets, Ltd., a partnership of Utah

Filed Feb. 13, 1969, Ser. No. 15,760

Term of patent 14 years

Int. Cl. D29—01

U.S. Cl. D72—1

FIG. 1.

FIG. 2.

FIG. 3.

FIG. 1 is a front plan view of a design for a housing for fire detector embodying this invention.

FIG. 2 is a side elevational view of FIG. 1.

FIG. 3 is an enlarged elevational view shown partly in section, the section being taken on line III—III of FIG. 1, and the housing being fragmentarily shown for convenience of illustration.

I claim:

The ornamental design for a housing for fire detector, as shown and described.
